US00D943880S

(12) **United States Design Patent** (10) **Patent No.:** **US D943,880 S**
Bruns et al. (45) **Date of Patent:** **** Feb. 22, 2022**

(54) **SHOE MIDSOLE**

(71) Applicant: **adidas AG**, Herzogenaurach (DE)

(72) Inventors: **Falk Bruns**, Nuremberg (DE); **Marius Jung**, Nuremberg (DE)

(73) Assignee: **adidas AG**, Herzogenaurach (DE)

(**) Term: **15 Years**

(21) Appl. No.: **29/730,512**

(22) Filed: **Apr. 6, 2020**

Related U.S. Application Data

(63) Continuation of application No. 29/641,223, filed on Mar. 20, 2018, now Pat. No. Des. 882,927, and a continuation of application No. 29/641,256, filed on Mar. 20, 2018, now Pat. No. Des. 882,928.

CLAIM

The ornamental design for a shoe midsole, as shown and described.

DESCRIPTION

FIG. 1 is a side view of a shoe midsole.

FIG. 2 is another side view of the shoe of FIG. 1.

FIG. 3 is a front view of the shoe of FIG. 1.

FIG. 4 is a back view of the shoe of FIG. 1.

FIG. 5 is a top view of the shoe of FIG. 1.

FIG. 6 is a bottom view of the shoe of FIG. 1; and,

FIG. 7 is a perspective view of the shoe of FIG. 1.

The broken lines surrounding the shoe midsole show boundary that form no part of the claimed design. Portions of the shoe outside of the broken lines show environment that form no part of the claimed design.

1 Claim, 7 Drawing Sheets
